UNITED STATES PATENT OFFICE.

JAMES C. GARNER, OF DALLAS, AND CHARLES S. REYNOLDS, OF HOUSTON, TEXAS,
ASSIGNORS, BY MESNE ASSIGNMENTS, TO GARNER REGIN MACHINERY COMPANY,
OF HOUSTON, TEXAS, A CORPORATION OF TEXAS.

COTTON CLEANER AND RENOVATOR.

1,180,133.

Specification of Letters Patent. Patented Apr. 18, 1916.

Application filed July 7, 1911, Serial No. 637,353. Renewed February 21, 1916. Serial No. 79,796.

To all whom it may concern:

Be it known that we, JAMES C. GARNER, residing at Dallas, in the county of Dallas and State of Texas, and CHARLES S. REYNOLDS, residing at Houston, in the county of Harris and State of Texas, citizens of the United States, have invented certain new and useful Improvements in Cotton Cleaners and Renovators, of which the following 10 is a specification, reference being had therein to the accompanying drawings.

This invention relates to machines for cleaning and renovating cotton and other similar fibrous materials.

15 In the cotton industry as it now exists a considerable amount of so-called second or low-grade cotton comes upon the market and commands a relatively low price. This cotton comes from various sources, but one of 20 the sources is found in the lint which falls from the gins in the regular process of ginning, and the lint which falls from the presses in pressing the cotton. Such waste cotton falling upon the floor is swept up as 25 it accumulates and is finally baled, together with the trash and dirt which naturally accumulates with it. Other sources of this second grade cotton might be pointed out, but it is sufficient to note that while coming 30 from various sources, the cotton fiber is in large part of comparatively good quality, its defects being largely due to its tangled and trashy condition. It has been found that the cotton fiber in such a condition can be 35 cleaned and renovated so that the resulting product compares very favorably with the cotton which is rated on the market as first-grade. In carrying out such a cleaning and renovating process in accordance with the 40 present invention, the cotton which has been pressed solid in bales is first opened up, partially separated and fluffed and is then still further separated into minute flakes, being finally condensed and pressed. During the 45 preliminary opening up and fluffing of the cotton the coarser and heavier particles of the dirt and other foreign materials are separated, and in the subsequent final separation of the fiber, the latter is thoroughly straight- 50 ened out and the last traces of dirt are separated.

The present invention relates more especially to the means which are employed in

the final separation of the fiber during which it is thoroughly straightened out and 55 the last traces of dirt are removed, and the invention has for its general object the provision of efficient and effective devices for performing this work.

The objects of the invention more specifically stated are the provision of an improved saw or picker drum for working the fiber, the provision of improved means for separating the dirt or impurities from the fiber when it is opened up or disintegrated 60 by the saw drum, and the provision of improved devices for separating and handling such parts of the fiber as are not thoroughly cleaned and renovated so that they can be subjected to a second treatment. The manner of attaining this, as well as any additional objects of the invention, will be readily understood from the following description in connection with the accompanying drawings. In the drawings—Figure 1 is a 70 right side elevation of a machine embodying the invention in its preferred form. Fig. 2 is a left side elevation of the machine. Fig. 3 is a plan view of the machine, a part thereof being broken away. Fig. 4 is a vertical 75 longitudinal sectional view of the machine. Fig. 5 is a vertical sectional view of the speed changing device which drives one of the feeding or stuffing rolls. Fig. 6 is a sectional view of the shaking grate or screen, 80 taken on the line 6—6 of Fig. 4. Fig. 7 is a side elevation of the improved saw drum employed, the saws being shown in their unflexed condition ready for sharpening, and a portion of the drum being broken away to 85 permit illustration on a larger scale. Fig. 8 is a similar view of the saw drum showing the saws flexed or crimped as they are when in operation in the machine. Fig. 9 is a transverse sectional view of the saw drum. 90

95 Referring in detail to the construction illustrated, 1 designates as an entirety the frame of the machine. This frame comprises upright side sections 2 and 3 having suitable pedestals 2^a and 3^a, and these side 100 parts of the frame are rigidly connected by transverse frame sections such as those at 4 and 5. In the inlet or mouth 6 at the front end of the machine are mounted two parallel stuffing rollers 7 and 8. These 105 rollers are carried by shafts 9 and 10 re-

spectively, which are mounted in suitable bearings in the frame of the machine. Preferably the shaft 9 is mounted in stationary bearings and is provided with suitable driving devices which will presently be referred to. The shaft 10, however, is preferably mounted in bearings 11 and 12 which are slidably mounted in guides carried by the main frame and are yieldingly pressed toward the shaft 9 by springs 13 and 14 respectively.

Beneath the stuffing rollers 7, 8 is arranged a conveyer belt or apron 15 which is carried by rollers 16 and 17 mounted on shafts 18 and 19 respectively. The roller 17 is disposed at a higher elevation than the roller 16, so that the belt 15 inclines upward and rearward.

20 is a belt tightening roller carried in movable bearings 21 and 22 which can be adjusted up and down by means of the screws 23 and 24 respectively to adjust the tension of the belt 15. Above the conveyer belt 15 is a second conveyer belt 25 which runs over rollers 26 and 27. The roller 26 is mounted on a transverse shaft 28 which is disposed in a vertical plane between the shafts 18 and 19, and the roller 27 is mounted on a transverse shaft 29. The shaft 28 30 is disposed higher than the shaft 29 and the latter is arranged directly above and relatively close to the shaft 19 so that the lower run of the belt 25 inclines downward and rearward. Thus the lower run of the belt 25 and the upper run of the belt 15 are arranged to converge and form a rearwardly contracting passage-way.

30 is a belt tightening roller mounted in a manner similar to the mounting of the roller 20 and designed to adjust the tension of the belt 25. The shaft 29 is mounted in 40 sliding bearing plates 31 and 32, which are pressed yieldingly downward by springs 33 and 34 respectively, each spring being interposed between its bearing plate and a nut 35 on a threaded rod 36 which is carried by a lug 37 on the frame of the machine.

Directly behind the rollers 17 and 27 are arranged a pair of feeding and gripping rollers 38 and 39. The roller 38 is carried by a shaft 40, which is mounted in stationary bearings on the machine frame, and the roller 39 is carried by a shaft 41, which is mounted in bearings carried by the yieldingly mounted plates 31 and 32. The rollers 38 and 39 are preferably corrugated, as indicated in Fig. 4.

60 Directly behind the feeding and gripping rollers 38 and 39 is arranged a saw drum or picker drum. This drum comprises a series of saw disks 42 which are mounted on a transverse shaft 43. This shaft is mounted in bearings 44 and 45 which have screw adjusting devices 46 to adjust the bearings forward or backward along ap-

proximately horizontal lines. The saw disks are prevented from turning on the shaft 43 by means of a key 47, or other suitable device, but are free to slide axially on the shaft. The saws are interposed between two heads or clamping disks 48, 49 on the shaft 43 and these clamping disks can be forced toward each other by means of nuts 50 and 51. The saw disks are secured in definite spaced relation to each other by means of spacing blocks or washers 52, 52, which are interposed between the disks and which are held in position by means of rods 53, 53 and 54, 54. Each of the rods 53, 53 is mounted at one end in a boss or block 48^a on the clamping head or disk 48, and the rods 54, 54 are similarly mounted in bosses 49^a on the head 49.

It will be observed on reference to Figs. 7, 8 and 9 that the rods 53 and bosses 48^a are diametrically opposite each other as are also the rods 54 and bosses 49^a and that the two sets of rods and bosses are disposed 90° apart. The saw disks are normally plain or flat, as shown in Fig. 7, but they are made thin enough so that they can be flexed or crimped and are made of a material having sufficient elasticity so that they will return to their normal form if the flexing forces are removed.

In constructing the drum the parts are first assembled in the positions shown in Fig. 7, and then one or both of the nuts 50 and 51 are screwed toward each other, whereupon the pressure of the lugs 48, 48^a and 49^a, 49 against the saw disks causes the latter to be flexed or crimped, as shown in Fig. 8. The saw disks when thus crimped have mutually overlapping parts, so that when the saw drum is rotated every point in a line along the surface thereof is touched four times during each rotation. The clamping head 48 is preferably provided with holes 55, and the head 49 with holes 56 to receive the ends of the rods 54 and 53 respectively when the saw disks are compressed as in Fig. 8.

When the saws are in operation they are crimped or flexed, as in Fig. 8, but when, after continued use, the teeth of the saws become dull or worn and it is desirable to sharpen or gum them the clamping heads are loosened up to permit the saw disks to swing back to their normal flat form and then they can readily be sharpened. In fact, when the saws have been thus restored to their flat form, they can be sharpened or gummed by the standard machines which are commonly employed for this purpose, whereas such gumming machines cannot be used at all upon the saws when in their crimped or flexed form.

The saw drum is arranged to run relatively close to the feeding and gripping rollers 38 and 39, as indicated in Fig. 4. Be- 130

neath the saw drum is arranged a mote-brush or drum 57 mounted upon a transverse shaft 58. The shaft 58 is mounted in adjustable bearings 58^a, 58^b, so that the mote-brush can be adjusted toward and from the periphery of the saw drum. The mote-brush is arranged to run close to the toothed periphery of the saw drum and in the opposite direction, the function of the brush 10 being to disengage from the saw teeth any foreign particles or matted bits of fiber of sufficient size to protrude beyond the fine straight particles of fiber adhering to the saw teeth.

15 Beneath the mote brush and the saw drum is suspended an inclined screen or grate 59. This screen or grate comprises a suitable frame structure upon which is mounted a series of longitudinally disposed beveled bars 60. At its upper front end the screen is supported by a transverse shaft 61 and eccentrics 62 thereon which fit in apertures in the screen frame. At its rear lower end the screen is supported by swinging links 63 25 the upper ends of which are secured to the machine frame. It will be seen that when the shaft 61 and its eccentrics 62 are rotated the screen is given a backward and forward and up and down shaking motion.

30 Directly beneath the lower end of the grate or screen 59 is a transversely arranged conveyer belt 64 carried on suitable rollers 65, one of which can be driven, as by a belt 66.

35 Directly behind the saw drum is a rapidly moving cylindrical doffing brush 67 and this doffing brush is carried by a transverse shaft 68 which is mounted in bearings 69 and 70 and which can be adjusted to move the brush toward or from a periphery of the saw drum. The casing part 5 closes the space above the doffing brush and the space below said brush is inclosed by a curved casing plate 71. 72 is a pipe leading from the casing surrounding the doffing brush into a 40 transversely arranged trunk or conduit 73 into which the fiber after treatment is discharged and conveyed away.

45 The various rotary parts which have been referred to above are driven by the following devices:

50 74 is a belt driven by any suitable power shaft. This belt passes around and drives a pulley 75 on the shaft 43 of the saw drum, thence around an idle pulley 76 and thence 55 around the pulley 77 on the shaft 68 of the doffing brush. The belt 74 thus serves to drive the saw drum in a counter-clock-wise direction and the doffing brush in a clockwise direction, as viewed in Fig. 4, and as 60 the belt pulley 77 is much smaller than the pulley 75 the doffing brush is driven at much higher peripheral speed than the saw drum. The shaft 43 carries at its end opposite the pulley 75 a pulley 78, and in line with this 65 pulley is a pulley 79 on the shaft 58 of the

mote-brush, the pulley 79 being driven from the pulley 78 by a belt 80. As the mote-brush is mounted to be adjusted toward and from the saw drum, a belt tightening pulley 81 on the swinging arm 82 is provided. 6 As the pulley 79 is small in relation to the pulley 78, the mote-brush is driven at a much higher speed than the saw drum.

75 83 is a belt pulley mounted on shaft 43 of the saw drum outside of the pulley 78, and 84 is a pulley mounted upon the short shaft 85 which has a bearing support at one end on the main frame part 2 and at its other end in the bracket 86 carried by said frame 2. The pulley 84 is driven from the pulley 80 83 by a belt 87. 88 is a spur gear on the shaft 85 and in mesh therewith is a gear 89 on the eccentric shaft 61 of the screen 59, the latter being thus driven from the shaft 85.

85 90 is a shaft having a bearing support 91 on the main frame and a bearing 92 carried by the bracket 86. The lower rear end of the shaft 90 carries a bevel pinion 93 which meshes with a bevel gear 94 on the shaft 85. At its front end the shaft 90 carries a worm 90 95 which operatively engages worm wheels 96 and 97 on the shafts 18 and 28 respectively. The shaft 90 is thus driven from the shaft 85 and serves in turn to drive at a reduced speed the conveyer belt rollers 16 95 and 26.

95 The roller shafts 19 and 29, which are driven by the conveyer belts 15 and 25 respectively, carry at their ends spur gears 98, 98 and 99, 99 respectively. Each of the 100 gears 98 meshes with an idle gear 100 which in turn meshes with and drives a gear 101 on the shaft 40 of the feeding and gripping roller 38. Similarly each of the gears 99 meshes with an idle gear 102 which in turn 105 drives a gear 103 on the shaft 41 of the upper feed roller 39. The feed rollers 38 and 39 are thus driven from the rollers 17 and 27 respectively.

105 The shaft 28 carries in addition to the 110 worm wheel 97 a sprocket wheel 104, and in line with this wheel is a sprocket wheel 105 mounted on a short shaft 106, carried by a bearing bracket 107. A chain passing over the sprocket wheels serves to drive the shaft 115 106. The shaft 9 of the stuffing roller 7 is driven from the shaft 106 preferably through a change speed gear. As shown, this gear is of the cone-pulley type, a cone-pulley 108 being mounted on the shaft 106 120 and a similar pulley 109 being oppositely disposed on the shaft 9. A short belt 110 runs between the adjacent surfaces of the cone-pulleys and serves to transmit the movement of the pulley 108 to the pulley 125 109 by frictional engagement.

111 is a belt shifter mounted on a bracket-arm or rod 112, and 113 is a set screw for holding the belt shifter in adjusted position. With these latter driving connections it will 130

be seen that the stuffing roller 7 is positively driven from the shaft 28 of the upper conveyer belt.

In the operation of the machine the cotton or other fiber, which has been opened up, fluffed and partially cleaned and renovated, is fed into the mouth 6 of the machine upon the stuffing rollers 7 and 8. As one of these rollers is positively driven the fiber is caught and fed downward upon the lower conveyer belt 15. This belt carries the cotton rearward and in conjunction with the upper belt 25 simultaneously advances and compresses the cotton so as to form it into a compact and more or less homogeneous bat.

As the bat of fiber passes from between the conveyer belts 15 and 25 it is received by the feeding and gripping rollers 38 and 20 39. The corrugated surfaces of these rolls grip the bat of fiber firmly and feed it slowly toward and against the rapidly moving toothed surface of the saw drum. As this drum rotates the entire end of the bat 25 is covered several times during each rotation of the drum by the saw teeth thereof, this result being secured by reason of the crimped or flexed formation of the saw disks. As the saw teeth in their rapid movement engage the end of the bat of fiber they separate or strip minute parts of the fiber from the bat, carrying them downward and rearward on the rapidly moving surface of the drum. During this movement of the 30 35 finely divided fiber any particles of dirt or impurities which adhere to the fiber are separated by the combined action of gravity and centrifugal force, such dirt or impurities falling through the shaking screen 59 upon the floor, where it can from time to time be gathered up.

If the fiber as it is fed against the saw drum is in a matted condition so that some of the fibers are not straightened out by the 45 action of the saw teeth as they strip the fiber from the bat, such matted bits of the fiber will project from the surface of the saw drum somewhat farther than the straightened and unmatted fibers, and any such bits 50 of matted fiber will be engaged and knocked from the saw drum by the mote-brush 57. Fiber thus removed from the saw drum falls upon the shaking grate or screen 59 and slides upon the grate bars to the lower 55 end thereof where it is delivered onto the conveyer belt 64. This conveyer can be arranged to deliver at any desired point and the fiber so delivered can be subjected to a second treatment.

60 The straightened and purified fiber adheres to the saw drum and is finally removed therefrom by the doffing brush 67, which, running at a high speed, strips the fiber from the saw teeth and carries it up- 65 ward and over to the discharge conduit 72,

where it is thrown from the brush under the combined action of centrifugal force and air suction in the air trunk 73, said suction being produced in any suitable manner.

The cotton as it is delivered into the 70 trunk 73 is in a thoroughly purified and renovated condition, practically all foreign particles having been separated and the fibers having been thoroughly straightened out, and, of course, the fiber is in a very 75 light and fluffy condition. In this state the fiber can be carried from the trunk 73 to a condenser and after the air has been pressed from it, it can be pressed in bales 80 or other desired form.

When, after continued use, the saw teeth become dull and worn they can readily be sharpened by loosening up the clamping heads of the drum to permit the saw disks to spring back to flat form so that efficient 85 gumming tools can readily be used upon the saws. After sharpening, the saws are again flexed or crimped by tightening up the clamping heads.

The periphery of the saw drum may at 90 any time be adjusted toward or from the feeding and gripping rollers 38 and 39 by adjusting the bearings 44, 45 of the drum shaft 43. Similarly the mote-brush 57 and the doffing brush 67 can be adjusted toward 95 or from the saw drum as wear of the brushes or other conditions may require.

We do not herein present claims for the novel features incident to the combining of the rolls, the picker drum, the doffing device, the inclined grate, etc., preferring to 100 present claims herein for the novel features incident to the picker drum, but we reserve the right to present claims for the other subjects-matter in other applications 105 about to be filed.

One of the novel matters incident to the drum which we have shown and described is that it is made up of separable radially arranged axially spaced disks secured rigidly to a shaft, the resulting drum-like body having its teeth so arranged that as they rotate they intersect, at every point, the line parallel to the axis and passing horizontally through the edge or front end of the cotton ribbon or bat so that every particle of the fiber and every particle of dust, sand or foreign material is impinged upon by a tooth, no matter at what point along said line it may be. The disk saws being separable they, or any one of them, can be taken out at any time for sharpening or replacing by another. As they are axially spaced there is a chamber or space between each one and the next which can receive material to such an extent as to prevent the teeth from becoming quickly clogged and as these spaces or chambers are themselves radial and without obstructions, radially, the centrifugal action of the drum instantly whirls 115 120 125 the fiber and the material so that it is carried to the discharge conduit 72.

outward, freeing any materials that tend to accumulate therein; and air currents can pass without impediment directly through these passages to keep them clean. This is

5 a contra-distinction from the disks that are arranged non-radially, that is, are arranged in planes that are inclined to the axis of rotation.

What we claim is:—

10 1. A picker drum for fiber cleaning machines comprising in combination a rotatable shaft, a series of elastic saw disks thereon, said disks being movable axially on the shaft but held against rotation relative thereto, means for spacing the disks from each other, and clamping devices for securing the disks rigidly together and for flexing their peripheries axially, said clamping devices being constructed to be readily 15 loosened to permit the disks to spring back to flat form whereby they can readily be sharpened.

20 2. A picker drum for fiber cleaning machines comprising a rotatable shaft, a series of elastic saw disks mounted thereon, said disks being movable axially of the shaft but held against rotation relative thereto, means for spacing the disks from each other, and clamping heads on the shaft between which the disks are arranged, one of said clamping heads being adjustable axially of the shaft and adapted when forced toward the other head to flex the peripheries of the disks axially, said clamping head being readily adjustable to loosen the disks and permit them to spring back to flat form so that they can readily be sharpened.

25 3. A picker drum for fiber cleaning machines comprising in combination a rotatable shaft, a series of elastic saw disks mounted thereon, said disks being movable axially of the shaft but held against rotation relative thereto, means for spacing the disks from each other, a pair of clamping heads on the shaft between which the saw disks are arranged, one of said heads being adjustable toward the other to clamp the saw disks together, and blocks interposed between each clamping head and its adjacent saw disk, the blocks of one head being offset angularly with respect to those of the other head whereby the saw disks are flexed axially when the clamping heads are forced 30 together.

40 4. A picker drum for fiber cleaning machines comprising in combination a rotatable shaft, a series of elastic saw disks mounted thereon, said disks being movable axially of the shaft but held against rotation relative thereto, means for spacing the disks from each other, a pair of clamping heads on the shaft between which the saw disks are arranged, a nut on the shaft for forcing 45 one of the heads toward the other, and

means interposed between the clamping heads and the adjacent saw disks to axially flex or crimp the saw disks when the clamping heads are forced together, the adjustable clamping head being readily movable to 50 loosen the saw disks and permit them to spring back to flat form so that they can readily be sharpened.

5. In a cotton cleaning or re-ginning mechanism, a toothed cylinder formed of 55 separable, peripherally toothed, axially spaced disks clamped together, each disk being, as an entirety, radially disposed in relation to the axis of the cylinder and being flexible on or around lines passing across the 60 faces of the disks and being flexed substantially as set forth to position the teeth of the cylinder, as an entirety, as described whereby they will intersect at all points lines which are parallel to the axis and peripheral 65 to the surface generated by said teeth during their rotation.

6. In a cotton cleaning or re-ginning mechanism, a toothed cylinder formed of 70 separable, peripherally toothed, flexible, 75 elastic, axially spaced disks clamped together, each of said disks being, as an entirety, radially disposed in relation to the axis of the cylinder, and clamping devices carried by the cylinder and adapted to flex 80 the disks substantially as set forth to cause the teeth of the cylinder, as an entirety, to intersect at all points lines parallel to the axis and peripheral to the surface generated by said teeth during their rotation.

7. A picker drum for fiber cleaning machines comprising in combination a series of elastic saw disks, a plurality of series of spacing blocks of which each series is arranged along a line parallel to and radially 85 distant from the axis of the drum, and clamping heads between which the disks are arranged, one of said heads being adapted to exert pressure against the adjacent saw disk at points in line with alternate series of said 90 spacing blocks and the other clamping head being adapted to exert pressure on its adjacent saw disk at points in line with the other series of spacing blocks, whereby the saw disks are flexed or offset in the direction of the drum axis and securely clamped 95 together by the said heads.

8. A picker drum for fiber cleaning machines comprising in combination a series of elastic saw disks, a plurality of series 100 of spacing blocks arranged between the disks on lines parallel to and radially distant from the axis of the drum, a series of rods extending through the saw disks and the said spacing blocks and adapted to hold the 105 latter in position in relation to the saw disks, and clamping heads between which the saw disks are arranged, one of said heads being adapted to exert pressure against the adjacent saw disk at points in 110

line with alternate series of the said spacing blocks and the other clamping head being adapted to exert pressure on its adjacent saw disk at points in line with the other 5 series of spacing blocks, whereby the saw disks are flexed or offset in the direction of the drum axis and securely clamped together by the said heads.

9. A picker drum for fiber cleaning machines comprising in combination a series of elastic saw disks having their central parts cut away, a plurality of series of spacing blocks of which each series is arranged along a line parallel to and radially distant from 10 the axis of the drum, and clamping heads between which the disks are arranged, one of said heads being adapted to exert pressure against the adjacent saw disk at points in line with alternate series of said spacing 15 blocks and the other clamping head being adapted to exert pressure on its adjacent saw disk at points in line with the other series of spacing blocks, whereby the saw disks are flexed or offset in the direction of 20 the drum axis and securely clamped together by the said heads.

10. In a machine for separating cotton fibers from each other, a picking drum formed of a series of normally flat toothed 25 disks secured together on a common axis, a

series of sets of disk flexing devices, one of each set bearing against each disk at a point remote from the axis and holding a portion of the periphery of said disk flexed away from the transverse planes normally occupied by the disk when flat, and suitable abutments carried by the cylinder reacting on the flexing devices. 35

11. A drum formed of a series of normally flat disks secured together on a common axis, a series of sets of disk flexing devices, one of each set bearing against each disk at points remote from the axis and those bearing against each disk pressing against it alternately around the axis in 40 opposite directions and each flexing device holding a part of the periphery of the disk flexed away from the transverse plane normally occupied by the disk when flat, and suitable abutments for the flexing devices 45 carried by the drum. 50

In testimony whereof we affix our signatures, in the presence of witnesses.
